UNITED STATES PATENT OFFICE.

HARRY M. PFLAGER, OF ST. LOUIS, MISSOURI, ASSIGNOR TO COMMONWEALTH STEEL
CAR COMPANY, OF ST. LOUIS, MISSOURI, A CORPORATION OF NEW JERSEY.

ARTICULATED CAR UNDERFRAME.

Application filed December 28, 1922. Serial No. 609,522.

To all whom it may concern:

Be it known that I, HARRY M. PFLAGER, a citizen of the United States, residing at the city of St. Louis, State of Missouri, have 5 invented a certain new and useful Improvement in Articulated Car Underframes, of which the following is a full, clear, and exact description, such as will enable others skilled in the art to which it appertains to 10 make and use the same, reference being had to the accompanying drawings, forming part of this application.

My invention relates to railway rolling stock and consists in an improved platform 15 or underframe construction for use in articulated cars where two adjacent cars have their ends mounted upon a common truck.

The object of my invention is to form 20 truck engaging elements integral with the car end sill or buffer member thereby eliminating a large amount of machine work necessary to fit separate units together and also containing a rigidity which is greater than can be provided in assembled parts and 25 which is permanent.

In the accompanying drawings which illustrate a selected embodiment of my invention,

Figure 1 is a top view of the platform 30 casting having center and side bearings formed integral thereon.

Figure 2 is a longitudinal section through two such castings on adjacent cars mounted upon a common truck.

Figure 3 is a side elevation of one of the 35 platform castings.

The platform casting is preferably of the cast steel type now in general use and comprises center sill portions 1, side sill portions 40 2, cross beam portions 3, and an end sill or 2, buffer portion 4. Cast integral with the latter portion is a centrally located center bearing member 5 and spaced therefrom along the end sill 4 are integral side bearing 45 elements 6. The projection which forms the center bearing element 5 extends downwardly and forwardly from the end sill 4 and its lower surface 7 is convex and adapted to be seated on concave upper surface 8 of 50 a truck bolster center plate 9. The upper surface of the projecting portion of element 5 is concave to correspond to the surface 8 of the truck center plate 9 and is adapted to receive the lower face of another body 55 center bearing element 10 extending from

the end sill 11 on an adjacent car and to support the body of the latter.

The side bearing members 6 extend downwardly from the end sill and have lower surfaces adapted to engage the upwardly 60 facing surfaces of truck side bearings (not shown) which may be of any type now in use.

Both the center bearing and side bearing elements are reinforced by suitable webs, as 65 shown, and the particular location and contour of the projecting bearing elements upon the end sill and the stiffening webs referred to may be varied according to conditions and different types of trucks with which the cars 70 are to be used.

When these center plates and side bearings are made integral with the platform or underframe structure, the drilling of bolt or rivet holes through the underframe member and the machining of the underframe 75 and bearing members to secure proper fitting thereof is all eliminated and the resulting structure is more rigid and durable than the best of assembled constructions. 80

Various modifications in the details of the structure illustrated may be made without departing from the spirit of my invention as expressed in the appended claims.

I claim:

1. In a railway car underframe, a downwardly facing element formed integrally upon the end of the underframe projecting beyond the end of the underframe and adapted to be supported upon a car truck. 90

2. A railway car underframe including an end sill or buffer provided with integral center plate and side bearing elements extending downwardly and projecting outwardly therefrom and adapted to fit complementary truck elements. 95

3. In a one-piece platform casting for a railway car, an integral central projection on the forward end of said casting having a lower surface adapted to be seated on the 100 center plate of a truck extending beyond the end of the car.

4. In an underframe casting for a railway car, integral spaced projections on the forward end of said casting on opposite sides of the center thereof and having lower surfaces adapted to cooperate with the side bearings of a truck, the longitudinal center of which is beyond the front of the platform casting. 105 110

5. In a railway car underframe casting, a forwardly and downwardly extending integral projection on the front wall of the casting having a bottom contour complementary to the contour of a truck center plate and having a top contour whereby said projection may receive a lower surface of a similar projection upon an adjacent underframe and may support the latter.
6. In an articulated car underframe, a one-piece casting constituting a car plat-
- form, a member formed integrally thereon projecting beyond the end thereof and adapted to form a body center bearing.
7. In an articulated car underframe, a one-piece casting constituting a car platform, a member formed integrally thereon projecting beyond the end thereof and adapted to form a body side bearing.

In testimony whereof I hereunto affix my ²⁰
signature this 5th day of Dec., 1922.

H. M. PFLAGER.

Certificate of Correction.

It is hereby certified that the assignment in Letters Patent No. 1,452,525, granted April 24, 1923, upon the application of Harry M. Pflager, of St. Louis, Missouri, for an improvement in "Articulated Car Underframes," was erroneously described and specified as "Commonwealth Steel Car Company," whereas said assignment should have been described and specified as *Commonwealth Steel Company*, as shown by the records of assignments in this office; and that the said Letters Patent should be read with this correction therein that the same may conform to the record of the case in the Patent Office.

Signed and sealed this 6th day of May, A. D. 1924.

[SEAL.]

KARL FENNING,
Acting Commissioner of Patents.
